UNITED STATES PATENT OFFICE.

JAMES ROSENBERG, OF CLEVELAND, OHIO.

DEVICE FOR PRINTING INTERSECTING LINES.

1,118,951.

Specification of Letters Patent.

Patented Dec. 1, 1914.

Application filed January 19, 1911, Serial No. 603,454. Renewed March 27, 1914. Serial No. 827,773.

To all whom it may concern:

Be it known that I, JAMES ROSENBERG, a citizen of the United States, residing at Cleveland, in the county of Cuyahoga and State of Ohio, have invented a certain new and useful Improvement in Devices for Printing Intersecting Lines, of which the following is a full, clear, and exact description, reference being had to the accompanying drawings.

This invention relates to devices for printing, and more particularly to devices that are adapted to print lines for blank forms, and especially intersecting lines.

In the embodiment of my invention shown herein the devices consist of rules which are so constructed as to permit assembling with their planes intersecting each other and with their printing edges in a common plane whereby, when locked up in the form, any suitable number of intersecting lines may be simultaneously printed, the number being limited only by the length of the rules, the number of slots therein, and the number of rules thus assembled. Moreover the distance between any two parallel lines may be varied as desired within the limit set by the length of the transverse rules, only restricted by the requirement that the distance between those lines must be a multiple of the distance between successive slots. Owing to the fact that this distance is small, the distance between lines can be adjusted suitably to all practical requirements. In the preferred form of my invention, each rule has two printing edges, thereby doubling its printing capacity.

Further and generally speaking, the invention may be defined as consisting of the combinations of parts and elements embodied in the claims hereto annexed and illustrated in the drawings forming part hereof, wherein—

Figure 1 represents a side elevation of a rule constructed in accordance with my invention, said rule being shown as designed for the purpose of printing at one edge a line consisting of a series of dashes; Fig. 2 is a side elevation of a slightly modified rule in which the back is also formed with a printing edge; Fig. 3 is a side elevation of yet another modification; Figs. 4 and 5 are cross sectional views taken on the lines 4—4 and 5—5 respectively of Figs. 1 and 2; Fig. 6 is a detail in perspective illustrating the manner in which any suitable number of

rules may be assembled in a form to produce any desired number of intersecting straight lines; and Fig. 7 is a plan view of a pair of intersecting rules both being of increased thickness and stiffness.

Describing the parts by reference numerals, 1 denotes a rule generally, the rule consisting of a body, the minimum width of which will be about one point and the rule being of any suitable material to adapt it for printing purposes. One edge 2 of the rule is slotted, the slots, in the preferred embodiment of my invention, extending inwardly a slightly greater distance than half the width of the rule, as shown at 3. These slots will preferably be of a width sufficiently greater than the thickness of the body of the complementary rules to receive such rules therebetween with practically no "play" or lost motion, insuring a snug fit.

Between the slots 3 the teeth 4 are formed, which teeth extend the full width of the rule and themselves form one of the printing edges. Obviously these teeth can be of the same thickness as the rule and such a construction is illustrated in Fig. 6 (see rule 1^a therein), but for several reasons I prefer to form these tongues and the metal of the rule in line therewith of greater thickness than the width at the bottom of the slots as clearly shown in all the views. This result is accomplished by taking a blank of the maximum thickness, cutting slots 3 entirely through the same, and then milling out or otherwise removing the metal in line with these slots so as to form grooves 5, having abrupt sides. The ends 6 of the teeth are generally reduced in thickness so as to print a narrow line, and the back of the rule can be treated in any desired manner. In Figs. 1, 4, and 6 it is shown as simply squared off as at 7 to serve as a base, in Fig. 2 it is tapered or reduced in thickness to form a printing edge 7^a, and in Fig. 3 it is formed, as shown at 7^b, for printing spaced characters instead of a line. In all cases the slotted edges of the rules will print broken lines while the opposite edge may be employed either to print straight lines or any desired characters.

Likewise the ends of the teeth can be notched or formed to print other than simple dashes, if desired, as shown at 7^c in Fig. 6.

While a single rule may be employed or a series of such rules arranged parallel to each other may be employed for the purpose of

printing at a single operation one or more lines and while my rules are each capable of printing different styles of lines by merely reversing the rules in the form, my invention lends itself to an arrangement of rules whereby it is possible to print at one operation any desired number of intersecting lines, the lines being of any desired style or appearance. In Fig. 6 there is illustrated the manner in which the rules may be assembled to secure this result, two pairs only of such rules being shown for purposes of illustration, it being apparent, however, that any desired number of rules may be employed, according to the number of lines which it is desired to print. The rule 1^a is of a somewhat simpler type since its greatest thickness must be slightly less than the width of the slots 3, and since these slots must be sufficiently near together so as not to separate unduly the characters printed by the tongues 4. This transverse rule is formed with printing edges 6^a and 7^a and its teeth 4^a are adapted to fit in the grooves 5 of the other rule while its back is received between the corresponding teeth of the first rule. Either edge of these rules can be employed for printing depending upon the style of work desired. The form shown in Figs. 1 and 4 cannot be reversed but has a wider base and hence a firmer bearing and is better suited to some kinds of heavy or long continued work. These rules will be locked in a form like any other printing appliance. The comparatively wide end of the rule 1 shown in Fig. 6 will usually be found to afford sufficient bearing for the rule end, but the comparatively narrow end of the transverse rule, will frequently necessitate the employment of a slotted support or attachment 8 which can be easily applied thereto.

As many rules, arranged side by side and suitably spaced, will be employed as the particular job will require. The rules which are to coöperate with this series of rules will then be applied in the manner shown in Fig. 6, namely, with their slotted edges receiving the solid bodies of the first series of rules and their own solid bodies inserted into the slots of the first series of rules and the ends of the rules of the second series being preferably supported in the same manner as the ends of the first rules. The width of the tongues 5 will be varied to suit varying conditions of use and will be preferably about the width of the slots. When the rules have been so arranged as to print the desired number of intersecting lines, the form will be locked up. The manner of slotting the rules allows the edges 4 of one series of rules to be in the same plane with the edges 2 of the other series and the width of the tongues allows an indefinite number of combinations of intersecting rules to be produced, making

a set of rules capable of practically universal application.

Obviously rules like 1^a can be used together if desired to the exclusion of rule 1. This arrangement, however, necessitates the use of the attachments 8 at all points, and fails to produce so rigid an arrangement, partly because of the less strength of the rules and partly because the steady engagement of the tongue 4^a with the sides of the grooves 5 is lacking.

In Fig. 7 I have illustrated an expedient for stiffening the transverse rules while still allowing their use in connection with the rules 1. This expedient consists in forming the sides of each tooth with ribs 9 spaced far enough from the edges of the teeth to permit the teeth to engage in the grooves 5, but serving in a marked degree to increase the stiffness of the teeth.

It will be understood that the length and thickness of the rules may be varied indefinitely to suit varying conditions that may arise and that the width of the tongues and of the slots therebetween may be varied indefinitely for the same purpose. By slotting the rules in either of the manners described, each rule retains a body portion of sufficient extent to prevent breakage in use. The form shown at 1 is preferred, since it provides a wider end area, holds the transverse rule more securely and is itself of greater stiffness.

Having thus described my invention, I claim:

1. As a new article of manufacture, a printer's rule consisting of a flat body portion having one side beveled or tapered to form a comparatively narrow printing edge, and having the other side formed with a plurality of spaced tongues separated by slots of equal width, the length of said tongues being not less than the width of the body portion of the rule and the ends of said tongues being in alinement and adapted to print a broken line, and said body portion being formed with grooves in alinement with said slots, said grooves terminating short of said narrow printing edge.

2. As a means for printing intersecting straight lines, a pair of rules, each rule consisting of a body portion having one edge straight and having the opposite edge formed with a plurality of spaced tongues separated by slots of equal width, the length of said tongues being not less than the width of the body portion of the other rule and the ends of said tongues being in alinement and adapted to print a broken line, the slots of each rule being adapted to receive the solid body portion of the other rule so as to bring their printing edges into the same plane when the rules are assembled, and the body portion of one of said rules being of greater thickness than the width of the slots of the

other rule and having grooves cut in its sides in alinement with its slots to permit assembling the rules together.

3. A device for printing intersecting straight lines comprising a rule consisting of a body portion having one side beveled or tapered to form a comparatively narrow printing edge and having the other side formed with a plurality of spaced tongues 10 separated by slots of equal width, the sides of said body portion being formed with transverse grooves in alinement with said slots and terminating short of said narrow edge, and a second rule also consisting of a 15 body portion adapted to fit in the slots of said first rule and having a printing edge adapted to be brought into the same plane with the printing edge of the first rule and having spaced teeth adapted to engage in the 20 grooves of said first rule.

4. A device for printing simultaneously a plurality of intersecting straight lines comprising a plurality of rules each having a straight edge at one side and having its other side formed with elongated teeth separated by slots of equal width, the ends of said teeth being all in one plane and adapted to print broken lines, the body portion of said rule having grooves in its sides alining with said slots; and a plurality of complementary rules adapted to fit in said slots and having spaced teeth in their lower edges adapted to straddle the body portions of said first rules and to engage the grooves therein; the length of the tongues and the width of the body portions of said two sets of rules being such as to permit the tongues of each to be brought into the same plane with the back edges of the other.

5. A device for printing intersecting straight lines comprising a rule consisting of a body portion having one side beveled or tapered to form a comparatively narrow printing edge and having the other side formed with a plurality of spaced tongues 40 separated by slots, the sides of said body portion being formed with transverse grooves in alinement with said slots and terminating short of said narrow edge, and a second rule also consisting of a body portion adapted to fit in the slots of said first rule and having a printing edge adapted to be brought into the same plane with the printing edge of the first rule and having spaced teeth adapted to engage in the 45 grooves of said first rule.

6. A device for printing intersecting straight lines comprising a rule consisting of a body portion having one side formed to provide a comparatively narrow printing 50 edge, and having the other side formed with a plurality of spaced tongues separated by slots, a side of said body portion being formed with transverse grooves in alinement 55 with said slots and terminating short of said narrow edge, and a second rule also consisting of a body portion adapted to fit in the slots of said first rule and having a printing edge adapted to be brought into the same plane with the printing edge of the first 60 rule, and having spaced teeth adapted to engage with the grooves of said first rule.

In testimony whereof, I hereunto affix my signature in the presence of two witnesses.

JAMES ROSENBERG.
